UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

ROTARY FOLDING MECHANISM.

1,203,464.

Specification of Letters Patent. Patented Oct. 31, 1916.

Application filed September 14, 1910. Serial No. 582,101.

To all whom it may concern:

Be it known that I, HENRY F. BECHMAN, of Battle Creek, in the county of Calhoun and State of Michigan, have invented certain new and useful Improvements in Rotary Folding Mechanism; and I hereby declare that the following is a full, clear, and exact description thereof, reference being had to the accompanying drawings, which form part of this specification.

This invention is an improvement in rotary sheet folding devices especially adapted for use in folding newspapers printed on rotary web presses; and the object is to provide a folder which can operate efficiently at very high speed.

The principal object of the present invention is to provide means for adjusting the folding blades simultaneously and to enable this object to be accomplished at one operation by one adjustment of parts so that the blades can be adjusted quickly and accurately and with great nicety by the ordinary pressman without requiring any particular skill in so doing.

I will now explain the invention in detail with reference to the embodiment thereof illustrated in the accompanying drawings which show one practical form of the invention and the description of which will enable any one familiar with the art to clearly understand the invention and adapt it for use in various styles of folders employing rotary cutting and folding devices.

In the drawings—Figure 1 is an end elevation of a rotary folding apparatus equipped with my invention. Fig. 2 is a side elevation thereof with the cutting cylinder and the stacker omitted. Fig. 3 is a sectional view on line 3—3, Fig. 2. Fig. 4 is an enlarged detail section of the bearings of shaft 5. Fig. 5 is an enlarged detail section of the devices for fastening plate 4.

In the drawings 1 designates the male cutting cylinder and 2 the female cutting and folding cylinder which may be mounted as usual on shaft 1^a, 2^a journaled in bearings on a suitable frame and provided with the usual cutting devices 1^b, 2^b. The cylinder 2 is also provided with the usual pin-operating devices as indicated at 2^c in the drawings; and within this cylinder at diametrically opposite points are two rotary tucking blades 3 which are mounted upon shafts 3^a journaled in bearings 4^a attached

to rocking plates 4 rotatably mounted upon the shaft 2^a, three of such plates being preferably used. The outermost plates 4 are provided with segmental racks 4^b on one side, which racks mesh with pinions or teeth 5^b on a shaft 5 journaled on the heads of cylinder 2. Shaft 5 projects at one end beyond the adjacent head of the cylinder and is squared as shown at 5^a, so that a wrench can be applied to this end 5^a, and by turning it the disks 4 can be rotatorially shifted on shaft 2^a so as to adjust the tucker blade shafts 3^a laterally forward or back as may be desired.

One or both of the end disks 4 may be provided with arc shaped slots 4^d through which pass bolts 4^e which are tapped into openings in the adjacent head of the cylinder, see Fig. 5, and the plates may be locked against rotation by tightening bolts 4^e, thereby locking the plates 4 and the tucker blades in their adjusted position. When the tucking blade shafts are to be adjusted the bolts 4^e are loosened and plates 4 are then shifted, by turning shaft 5 as described, to the desired position and then bolts 4^e are tightened so as to lock the plates 4 to the cylinder heads and thereby secure the tucker blades 3 in their adjusted position.

The blades 3 are rotated on their own axes as the cylinder 2 revolves, by means of pinions 3^c on one end of each shaft 3^a meshing with an internal gear 6 attached to the box in which shaft 2^a rotates and surrounding the shaft 2^a as usual. With the described arrangement and construction both tucker blades 3 can be adjusted at one movement; and as a considerable rotary movement of shaft 5 will impart but a slight rotary movement to the plate 4, it is possible to adjust the tucker blades simultaneously in the cylinder with the greatest nicety.

The novel means for adjusting the folding blades can be applied to different forms of rotary folders and I do not wish to limit myself to the particular construction thereof herein shown.

I have conventionally indicated in the drawings other parts of web folding apparatus usually employed in connection with the cylinders 1 and 2, the part marked 7, Figs. 1 and 3, representing part of the "cow-catcher" former at the apex of which are the first fold rolls 7^a, 7^b, from which the papers pass on between the cylinders 1 and 2 being

severed by the blade 1^a at the proper time, and carried on by the pins past the second fold rolls 8, 8^a between which the folded papers are tucked by the rotary blades 3 in the usual manner; and then they are dropped in front of the stacker 9. The roll 8^a is preferably journaled in arms 8^b attached to a rock shaft 8^c having crank arms 8^d to which are connected bolts 8^e transfixing rocking eyes 8^f attached to the frame, springs 8^g being interposed between the arms 8^d and the eyes 8^f to hold the roll 8^a yielding against or toward the roll 8. By adjusting the nuts 8^h on the outer ends of bolt 8^e the roll 8^a may be held at any desired distance from the roll 8, to prevent re-print or offset on papers passing between the said rolls, and to accommodate varying numbers of pages passing between the rolls. This device will also permit the passage of small irregularities which might jam and cause a clog between fixed rolls.

What I claim is:

1. In a folder, the combination of a folding cylinder, adjustable plates associated with the cylinder provided with diametrically opposite bearings for tucker blade shafts, tucker blade shafts journaled in said bearings, a rotatable shaft in the cylinder 25 beside said plates, gearing between said shaft and said plates for adjusting the latter rotatorially, and means for locking the plates when adjusted.
2. In rotary folding apparatus, the combination of cutting and folding cylinders, adjustable plates associated with the folding cylinder, tucker blade shafts journaled in said plates, tucker blades attached to said shafts, and means for rotating said tucker 30 blade shafts; with a shaft mounted in said folding cylinder beside the plates and gearing between the said shaft and plates for adjusting the latter.
3. In rotary folding apparatus, the combination of cutting and folding cylinders; adjustable plates associated with the folding cylinder, rotary tucker blade shafts journaled in said plates, and tucker blades attached to said shafts; with a shaft journaled in said folding cylinder beside the plates, gearing between said shaft and plates 45 for adjusting the latter, and bolts engaging slots in the plates for locking the plates when adjusted.
4. In rotary folding mechanism, a folding cylinder, adjustable plates associated with the cylinder, a rotary tucker blade mounted on said plates, and means for simul- 55

taneously adjusting the plates rotatorially independently of the cylinder. 60

5. In a rotary folder, a folding cylinder, adjustable plates associated with the cylinder, a rotary tucker blade journaled in said plates, and means for simultaneously adjusting the plates rotatorially of the cylinder. 65

6. In a rotary folder, a folding cylinder, adjustable plates associated with the cylinder, a tucker blade mounted on said plates, a rotatable shaft in the cylinder, and gearing between said shaft and plates, for adjusting the latter rotatorially. 70

7. In a rotary folder, a folding cylinder, adjustable plates associated with the cylinder, rotary tucker blades journaled in said plates, a rotatable shaft in the cylinder and gearing between said shaft and said plates for adjusting the latter rotatorially. 75

8. In a rotary folder, the combination of a folding cylinder, adjustable plates in the cylinder, a tucker blade mounted on said plates, means for simultaneously adjusting the plates rotatorially, and means for locking them when adjusted. 80

9. In a rotary folder, the combination of a folding cylinder, adjustable plates rotatably mounted in the cylinder and provided with diametrically opposite bearings for tucker blade shafts, rotary tucker blade shafts journaled in said bearings, means for simultaneously adjusting the plates rotatorially, and means for locking the plates when adjusted. 85 90

10. In a rotary folder, the combination of a folding cylinder, adjustable plates rotatably mounted in the cylinder, tucker blades mounted on said plates, a rotatable shaft in the cylinder, gearing between said shaft and said plates for adjusting the latter rotatorially, and means for locking the plates when adjusted. 95 100

11. In rotary folding apparatus, the combination of cutting and folding cylinders, adjustable plates within the folding cylinder, a pair of diametrically opposite tucker blade shafts journaled in said plates, tucker blades attached to said shafts, means for rotating said shafts, and means for rotatorially simultaneously adjusting said plates. 105

In testimony that I claim the foregoing as my own, I affix my signature in presence of two witnesses.

HENRY F. BECHMAN.
